UNITED STATES PATENT OFFICE.

WILLIS K. JACOBS, OF ST. PAUL, MINNESOTA.

CENTER SUPPORT FOR AWNING-ROLLERS.

1,111,590.

Specification of Letters Patent. Patented Sept. 22, 1914.

Application filed March 21, 1914. Serial No. 826,387.

To all whom it may concern:

Be it known that I, WILLIS K. JACOBS, a citizen of the United States, residing at St. Paul, in the county of Ramsey and State of Minnesota, have invented certain new and useful Improvements in Center Supports for Awning-Rollers, of which the following is a specification.

My invention relates to improvements in center supports for awning rollers, its objects being to provide an improved two part center support wherein the bottom or roller supporting member can be hung directly upon, and suspended from, the top member without the use of screws or bolts, and wherein the bottom member will be held in correct relation with the top member, and preferably be capable of some lateral play, so that it can accommodate itself to any tilting of the roller out of its normal horizontal position that may occur in ordinary use.

To these ends the invention consists in the construction, combination, and arrangement of parts hereinafter described and claimed.

In the accompanying drawings showing the preferred embodiment of the invention, Figure 1 is a perspective view of the center support with the two constituent members coupled together; Fig. 2 is a front elevation of the center support with a fragment of an awning roller supported therein; Fig. 3 is a side elevation of the center support with some parts broken away; showing the top member secured to the backboard or wall and the bottom member slipped part way over the top member; Fig. 4 is a vertical section through a center support secured in place upon the backboard or wall; Fig. 5 is a front elevation of the top member alone; and Fig. 6 is a rear elevation of the bottom member alone.

Generally speaking the invention comprises a top or bracket member adapted to be secured to fixed support and a bottom or roller supporting member adapted to be hung upon the top member.

In the embodiment of the invention shown in the drawings, the top member is a bracket having a shank 2 adapted to seat against and be secured upon, a backboard or wall A, and an upwardly and outwardly extending arm 3 in the end of which is journaled an anti-friction roller 4. The shank is here shown formed with holes 5 to receive one or more fastening screws or

bolts 6. The arm 3, which is preferably bowed upwardly, springs from the upper end of the shank 2, and is projected upwardly and outwardly therefrom, so as to leave between the arm and the wall or backboard a space or socket 7 wide enough to allow the hanger bar 12 of the lower member to drop freely therein, as hereinafter explained. In order to leave space enough for the hanger bar to seat firmly upon the top of the shank 2 without being wedged between the arm and the wall, the arm 3 is preferably constructed to spring from the outer or forward face of the shank, or rather from an outward offset or shoulder 8 formed thereon.

The bottom or suspension member consists of a skeleton frame having at the bottom an outwardly projecting roller support comprising two spaced arms 9 in which are journaled anti-friction rollers 10, and at the back an upwardly extending hanger. The hanger comprises two upright side members 11 connected at the top by means of a cross bar 12 which lies, preferably, in the same plane as the upright side members so that its rear face shall be flush with the rear face of the upright members. At the bottom of the hanger near the point of union between the hanger uprights and the roller supporting arms 9 the hanger uprights are connected by means of a cross bar 13. This is arranged upon the outer face of the uprights, so as to be outwardly offset therefrom, for the purpose hereinafter mentioned. The cross bar 12 is thin enough to drop freely within the socket 7 and seat upon the top of the shank 2, while the uprights 11 are spaced apart a distance somewhat greater than the width of the shank, so as not only to fit over the shank, but to allow for some play of lateral motion of the suspension member with reference to the shank when the members are coupled together, as shown in Figs. 1 and 4.

In use the top bracket is first secured or bolted upon the wall or backboard A which is to support the awning. The hanger of the bottom member is then slipped over the outwardly extending arm 3 of the top member, as illustrated in Fig. 3, this arm with its roller 4 passing freely through the opening in the hanger, until the cross bar 12 drops down into the socket 7 and upon the top of the shank 2 of the top member, as shown in Fig. 4. The upright side members 11 will

then seat and be braced against the wall or backboard on either side of the shank 2, while the bottom cross bar 13 will stand across the outer face of the shank and serve to brace the bottom member against the shank of the top member if the wall or backboard should not extend far enough down on the sides of the shank 2 to form a sufficient back support for the suspension member. The awning roller B is then inserted between the top and bottom members, and will rest centrally upon the rollers 10 of the lower or bottom member, with its ends supported in journal bearings (not shown) of any appropriate kind. Thus it will be seen that the center support is so constructed that it not only can be put in place with great ease and facility, but has great strength and weight supporting power, for the strain upon the suspension member and the weight of the awning will be not only downwardly upon the shank and its securing bolt, but torsional or angular, namely an outward pull at the top, which is exerted against the base of the arm 3, and an inward thrust at the bottom, which is received upon the face of the support or the shank. Furthermore the support is so constructed that it can be fastened upon a very small supporting surface, and space enough is left between the inner sides of the uprights 11 and the shank 2 to afford the suspension member sufficient swinging play to enable it to accommodate itself to such tilting of the awning roller out of its normal horizontal position as may occur in ordinary use.

I do not wish to limit myself to the exact structure shown in the drawings, for it is obvious that various modifications may be made therein without departing from the principle of the invention, the scope of which is defined in the claims.

I claim as my invention:

1. A center support for awning rollers comprising two separable members coöperating to hold an awning roller between them, namely a top member adapted to be secured upon a fixed support, and a bottom member adapted to be removably hung from the top member.

2. A center support for awning rollers comprising two separable members coöperating to hold an awning roller between them, namely a bracket member adapted to be secured upon a fixed support and having a retaining arm extending upwardly and outwardly from said support, and a suspension member having a skeleton hanger adapted to be hung from said arm with the top member of the hanger lodged in the space at the base of said arm between said arm and said fixed support.

3. A center support for awning rollers comprising two separable members coöperating to hold an awning roller between

them, namely a bracket member having a shank adapted to be secured upon a fixed support and a retaining arm extending upwardly and outwardly from the shank, and a suspension member having a skeleton hanger adapted to be removably hung from said arm with the top member of the hanger lying in the plane of the shank and lodged in the space between said arm and said fixed support.

4. A center support for awning rollers comprising separable bracket and suspension members, the bracket member having a shank adapted to be secured upon a fixed support and a retaining arm projected upwardly and outwardly from the outer face of the shank near the top thereof, whereby to leave a space above said shank and between said arm and said fixed support, and the suspension member having an upwardly extending skeleton hanger formed with a cross bar at the top, said hanger being adapted to be hung over said arm with its cross bar lodged in the space between said arm and said fixed support and resting upon the top of said shank.

5. A center support for awning rollers comprising separable top and bottom members, the top member having a shank adapted to be secured upon a fixed support and a retaining arm projected upwardly and outwardly from said shank, and the bottom member having a skeleton hanger comprising upright side members and a cross bar at the top, said hanger being adapted to be hung over said arm with its cross bar lodged in the space between said arm and said fixed support, the sides of the hanger being spaced apart a sufficient distance to receive said shank between them, whereby the hanger will lie in the same plane as the shank.

6. A center support for awning rollers comprising two separable members coöperating to hold an awning roller between them, namely a bracket member adapted to be secured upon a fixed support and having an outwardly and upwardly extending arm, and a suspension member adapted to be removably hung over said arm at the point where it springs away from said support, and means for bracing the lower part of the suspension member against the face of the bracket.

7. A center support for awning rollers comprising separable top and bottom members, the top member having a shank adapted to be secured upon a fixed support and a retaining arm projected upwardly and outwardly from said shank, and the suspension member having an upwardly extending hanger comprising side members and a cross bar at the top, said hanger being adapted to be hung over said arm with the cross bar lodged in the space between said arm and said fixed support and lying in the same

plane as the shank, and a brace connecting said side members near the bottom and being outwardly offset therefrom so as to lie in a plane outside the plane of the shank.

5 8. A center support for awning rollers comprising two separable members, namely a bracket member adapted to be secured upon a fixed support, and a suspension member adapted to be removably hung from the 10 bracket member, and means for preventing

the suspension member from moving laterally beyond a predetermined point with reference to the bracket member.

In testimony whereof I affix my signature in presence of two witnesses.

WILLIS K. JACOBS.
